(57) **CLAIM**

The ornamental design of a portable container and cover for emesis, as shown and described.

DESCRIPTION

FIG. 1 is a perspective view of the portable container and cover for emesis of our new design;

FIG. 2 is a front elevational view thereof, the rear elevational view being a mirror image thereof;

FIG. 3 is a side elevational view of the right side thereof;

FIG. 4 is a side elevational view of the left side thereof;

FIG. 5 is a top plan view thereof;

FIG. 6 is a bottom plan view thereof;

FIG. 7 is a top view looking in the direction of the arrow in FIG. 2 with the cover removed from the container; and, FIG. 8 is a top view similar to FIG. 7 with the cover on the container.
